UNITED STATES PATENT OFFICE.

LOGAN H. HOOPER AND RICHARD A. MURRAY, OF MUSKOGEE, OKLAHOMA.

CLASSIFICATION BOX.

Application filed March 31, 1924. Serial No. 703,291.

To all whom it may concern:

Be it known that we, LOGAN H. HOOPER and RICHARD A. MURRAY, citizens of the United States, residing at Muskogee, in the county of Muskogee and State of Oklahoma, have invented certain new and useful Improvements in Classification Boxes, of which the following is a specification.

This invention appertains to signaling devices and more particularly to the type known as a classification box and is an improvement over our pending application filed August 17, 1922, Serial #582,454.

The primary object of the present invention is the provision of means for associating the number of the engine with each classification box and novel means for operatively connecting a designating letter with one of the signaling arms or flags, whereby upon movement of the said signaling arm or flag, the designating letter will be brought into an operative and an inoperative position relative to the engine number.

Another object of the invention is the provision of a spring-wound roller associated with each classification box adjacent to the engine number having wound thereon a flexible shade upon which is printed a designating letter, and a flexible cable connecting the shade with one of the signaling arms, in such a manner that when the signaling arm is moved to its operative position, the shade will be moved downward to bring the designating letter to its operative position, and when the arm is moved to its inoperative non-signaling position, the shade will be returned to its normal inoperative position.

A further object of the invention is the provision of novel means for operating the signal arms or flags in both of the classification boxes from single feed or supply pipes located on one side of the locomotive.

A still further object of the invention is to provide an improved device of the above character, which will be durable and efficient in use, one that will be simple and easy to manufacture, and one which can be placed upon the market and incorporated with a locomotive at a small cost.

With these and other objects in view, the invention consists in the novel construction, arrangement and formation of parts, as will be hereinafter more specifically described,

claimed and illustrated in the accompanying drawings, in which drawings:

Figure 1 is a fragmentary top plan view of a locomotive with the invention applied thereto,

Figure 2 is a vertical section through one of the signaling devices,

Figure 3 is a perspective view of one of the flags associated with each signaling device,

Figure 4 is a longitudinal vertical section through the signaling device showing one of the flags arranged in a semi-displaying position,

Figure 5 is a perspective view of the outer end of the signaling device with one of the flags arranged in the displaying position,

Figure 6 is a fragmentary side elevation of one of the signaling devices showing the other signaling flag in its operative signaling position and showing the designating letter moved to its operative position relative to the engine number,

Figure 7 is a fragmentary longitudinal horizontal section through one of the signals showing one of the arms in its operative signaling position, and

Figure 8 is an enlarged fragmentary detailed vertical section through one of the signaling devices showing the shade carrying the designating letter pulled down to its operative position.

Referring now more particularly to the drawings, and wherein for the purpose of illustration is shown the preferred embodiment of this invention, the numeral 6 designates the forward end of a locomotive having the usual smoke stack 7 projecting upwardly therefrom, a signaling or classification box 8, which in the present instance consists of a rectangular casing is mounted at the forward end of the locomotive at each side thereof and projects laterally beyond the boiler as clearly shown in Figure 1. Any preferred means may be utilized for supporting these boxes on the locomotive. Each of the boxes are of identically the same construction and therefore only one will be described in detail for the sake of brevity.

The casing 8 includes a front wall 9, top and bottom walls 10 and 11, end walls 12 and 13, and a hinged rear wall 14. The front wall 9 is adapted to be arranged fac-

ing forwardly of the locomotive and is provided with an opening 15 or bull's-eye in the upper corner as clearly shown in Figures 4 and 5. This opening is covered by a transparent lens and is the color of the ordinary lens. The end wall 13 of the casing which is the end arranged the furthest from the locomotive is provided with a pair of spaced vertical slots 16 and 17 for a purpose which 10 will be hereinafter more fully described. This end of the casing in the upper rear corner is provided with an opening 18 which is covered by a transparent element or lens. The rear wall 14 is left plain with exception 15 of an opening 19 in its upper corner which opening is covered by a transparent element or lens, so that a source of light 20 may be seen by the engineer, so that at all times he will be informed whether or not 20 the casing 8 is properly illuminated. The source of light in the present instance consists of an incandescent light bulb which is situated at the inner end of the casing adjacent the top thereof. Extending trans- 25 versely through the outer lower corner of the casing 8 is a shaft 21 which has its opposite ends journaled in the front and rear walls 9 and 14 as shown in Figures 2 and 7 of the drawings. This shaft is prevented 30 from displacement by means of a collar 22 keyed to each end thereof. A pair of the so-called flags 23 and 24 are loosely mounted in spaced relation on the shaft and the same are preferably made of rigid mate- 35 rial such as hardwood, or metal. The flags are painted different colors and in the present instance the flag 23 is white, while the flag 24 is green. Each of the flags have secured to one side thereof a small pinion 25 40 each of which has an opening therethrough arranged concentric with the opening in its respective flag and through which the shaft 21 passes. The flag 24 is of an L-shape having an opening at the juncture of its two 45 arms for receiving the said shaft. The flag 23 consists of a straight body portion and is provided adjacent to its outer end with a bull's-eye 25. The inner end of this arm is provided with an opening through which 50 the shaft 21 passes. A coiled spring 27 is provided for each flag and has one of its ends secured to a flag and the opposite end to the bottom wall 11 of the casing. These springs normally tend to hold the flags 55 within the casing. It is to be noted that the arm of the flag 23 must be rotated at an arc of substantially one hundred and eighty (180) degrees so as to move the same to its signaling position, while the flag 24 60 only has to be moved through an arc of eighty (80) degrees. The flag 24 has its signaling arm provided with a transparent element 28 of a rectangular figure 8 and is the same color as the flag, while the other 65 arm of the flag 24 is provided with a bull's-

eye 29 which is adapted to align with the bull's-eye or opening 15 in the front wall 9 of the casing when the flag is moved to its signaling position. The flag 23 is provided with a transparent element 30 which 70 is also of practically the same color as the flag.

For projecting the flags from the casing to a displaying position a rack bar 31 is provided for each flag and is arranged 75 alongside of the flag so that the teeth of the rack bar will mesh with those of the respective pinions 25. These rack bars are held in engagement with the pinions by means of suitable brackets or guides. Spacing means 32 are arranged on the shaft so as to hold the flags in spaced relation.

In the present instance, each rack bar 31 constitutes the stem of a piston which is arranged within a cylinder 33 disposed at the forward end of the locomotive. These cylinders are connected to feed pipes 34 which can extend from any source of compressed air supply. It is to be noted that the pistons 33 on the left-hand side of the locomotive are connected by branch pipes 35 with the feed or supply pipes 34. Thus it is only necessary to provide a single pair of supply or feed pipes 34 for operating both of the signals on each side of the locomotive simultaneously. It is preferred to have this supply pipe 34 lead to the cab of the locomotive and air pressure there-through is controlled by the engineer so that by permitting air to enter into the cylinders 37 the flags will be caused to project from the casing, and when the air pressure in the pipe is released, the coil springs 27 will return the flags back to their positions within the casing. It is to be understood of course that the rack bars of the white flags are controlled independently from those of the green flags, and the white flags on the both sides of the locomotive may be simultaneously operated, and also the green flags 100 may be simultaneously operated.

In the present invention the front wall 9 of each casing is provided with a rectangular cut-out portion 36 adjacent to the incandescent lamp 20 and this opening has fitted therein a transparent plate 37 on which is painted or otherwise fixed the number of the locomotive indicated by the reference character 38 on the drawing.

The transparent plate 37 is left blank in front of a number of a locomotive 38 so that a designating letter, such as X in the present case as indicated by the reference character 39 in the drawings, can be placed in front of the locomotive number 38 when so desired. This designating letter X is pasted on or otherwise fixed to a suitable shade 40 which is wound about a spring roller 41. This spring roller 41 is similar to the ordinary shade rollers and is carried by suitable 120 125 130

brackets 42 secured to the inner face of the front wall 9 of the casing. The spring roller 41 normally tends to wind the shade 40 up thereon, and thus normally hide the 5 designating letter X from view.

This shade is operatively connected to the white flag 23, so that when the white flag is moved to its signaling position the shade will be pulled down against the tension of the spring roller 41 and position the 10 designating letter X in a signaling position. In order to operatively connect the shade with the arm a pull cord 43 is provided. The cord 43 has its upper end connected to the lower end of the shade and its 15 lower end connected to the flag 23 at a pointed space in the pivot point thereof. Suitable guide rollers 44 are provided for the pull cord 43 so as to insure the correct 20 guiding thereof during the movement of the flag. When the flag 23 is moved back to its inoperative position, it is obvious that the shade will be returned to its inoperative non-signaling position.

25 Changes in details may be made without departing from the spirit or the scope of this invention, but:

What we claim as new is:

1. A locomotive signaling appliance comprising an illuminated casing, a plurality of independently operable signal flags, an engine number plate carried by the casing, a movable designating letter associated with the casing, and means for operatively connecting the designating letter with one of the flags for causing the operation of said letter during the movement of the signaling arm.

2. In a locomotive signaling appliance, 40 an illuminated casing having an opening therein, a transparent plate fitted within the opening having the locomotive number affixed thereto, a movable designating letter adapted to be moved in front of and 45 away from said locomotive number, a sig-

naling flag pivotally mounted within the casing, means for moving the flag into and out of the casing, and means for operatively connecting the flag with the designating letter, as and for the purpose specified. 50

3. In a locomotive signaling device, an illuminated casing having an opening in the front wall thereof, a transparent plate fitted within said opening having the locomotive number affixed thereto, a flexible curtain 55 carried by the casing and arranged adjacent to the locomotive number having a designating letter affixed thereto, a signaling flag, means for moving the signaling flag into and out of the casing, and a pull cord 60 for operatively connecting the signaling flag with the curtain whereby upon movement of the flag, the curtain will be operated therewith.

4. In a locomotive signaling appliance, 65 an illuminated casing having an opening therein, a transparent plate fitted within the opening having the locomotive number affixed thereto, a movable flexible curtain arranged adjacent to the front end of the number having a designating letter affixed thereto, a spring-wound roller receiving the curtain and normally holding the same wound thereon, a signaling flag pivotally 70 mounted within the casing, means for moving the signaling flag to an operative signaling position and an inoperative non-signaling position, a pull cord operatively connecting the lower end of the curtain with the flag, so that upon movement of the flag 80 to a signaling position the shade will be moved to an exhibiting position.

In testimony whereof we affix our signatures in presence of two witnesses.
